REFRIGERATION SYSTEM

Velt Cowan Patterson, York, Pa., assignor to V. C. Patterson & Associates, Inc., York, Pa., a corporation of Pennsylvania

Application June 16, 1948, Serial No. 33,375

10 Claims. (Cl. 62—115)

1

This invention relates to refrigeration systems and more particularly to a liquid refrigerating circulating system for application to multi-story buildings.

In systems for supplying refrigeration to various floors or rooms of multi-story buildings a complete system may be installed on each floor, or a central system may be installed on one floor to furnish refrigeration to several or all floors. Where a complete system is provided on each floor, there is an expensive duplication of controls, pumps, condensers, storage tanks, and the like. Where a central system is provided on one floor, usually the lower floor, known systems are not completely satisfactory because of the problems which arise in distributing refrigerants to different floor levels at different heads and for variable demands. The recirculating system disclosed hereinafter eliminates many of the problems of duplicate systems and the distribution problems of central systems.

It is an object of this invention to provide an efficient central refrigeration system for multi-story buildings in which each floor level is furnished with adequate refrigeration regardless of the refrigeration demand on other floor levels of the building.

It is another object of this invention to provide a central refrigeration system for multi-story buildings for use with a recirculated liquid ammonia type of refrigerant.

It is another object of this invention to provide a liquid recirculating refrigeration system for multi-story buildings which facilitates individual temperature control of the refrigeration furnished to each floor or level.

It is another object of this invention to provide a refrigeration system for multi-story buildings in which the distribution apparatus on each level may be conveniently isolated from the space or spaces to be cooled on that level.

It is a further object of this invention to provide a double pumping liquid recirculating refrigeration system for multi-story buildings.

It is a still further object of this invention to provide a refrigeration system for multi-story buildings which provides an adequate distribution of liquid ammonia to each level to be refrigerated.

Other objects, advantages and features of 50

2

the present invention will become readily apparent from the following description of the embodiment illustrated in the accompanying drawings wherein:

5 Figure 1 is a diagrammatic illustration of a refrigeration system for a six-story building.

Figure 2 is a diagrammatic partial plan view of the preferred location of refrigeration apparatus provided on each of the upper levels of the 10 building shown in Figure 1.

Referring to the drawings, the exemplary embodiment of the invention is shown applied to a cold storage ware house having spaces 10 on five different levels which are to be refrigerated. The apparatus provided on the first or basement level 11 includes a master surge drum 12 for containing liquid and gaseous ammonia as a refrigerant medium. The top of the master surge drum 12 is connected by a conduit 13 to a compressor 14 which in turn is connected by conduit 15 to a condenser 16. The condenser 16 is connected to a receiver 17 which is connected by conduit 18 back to the master surge drum 12. Suitable controls such as a float switch 19 and an electromagnetic valve 20, of conventional character, may be provided to permit liquified ammonia to flow from the receiver 17 through high pressure conduit 18 to the master surge drum 12 as fast as it accumulates in the receiver or when the liquid level in receiver 17 rises above a selected point. Visual or other forms of gauges may be provided to indicate the liquid level in the master surge drum and in the receiver 17. The lower portion of the master surge drum 12 is connected by a 15 conduit 21 to the inlet of a high head ammonia pump 22. The pump 22 should be of sufficient capacity to pump to the top of the building about five times as much liquid ammonia as is estimated to be required to refrigerate all of the spaces 10.

The apparatus on each floor level of the building to be refrigerated may be identical on each level, and includes a surge drum 25, a low head ammonia pump 26 driven by a motor M, a distribution valve 27, a cooling coil or coils 28, and a thermostat 29. The coils 28 and the thermostat 29 are located in the space 10 to be cooled. The pump 26 pumps liquid ammonia from the surge drum 25 through the distribution valve 27 into the cooling coil 28. Space temperature is

controlled by the thermostat 29 which starts the pump 26 when more cooling is required and stops the pump 26 when the space temperature is low enough. The thermostats 29 may, of course, be adjustable and of conventional construction.

A circulation pipe 30 for liquid ammonia extends from the outlet of pump 22 to the top of the top surge drum 25. The return pipe 31 extends from the upper portion of the upper surge drum 25 downward to the upper portion of the master surge drum 12. Each surge drum 25 is connected to the return pipe 31 at two levels by valved connections 32 and 33. Valves 34, normally closed, are provided in the return pipe 31 between the entry points of each pair of connections 32 and 33.

During normal operation of the system described above, valves 34 in return line 31 are all closed and valves 32 and 33 are all open. Liquid ammonia is pumped by the pump 22 through conduit 30 into the top of the top surge drum 25. Liquid ammonia collects in the bottom portion of the top surge drum 25 and excess liquid ammonia flows through open valve 33 into the return pipe 31. Said excess then enters the top of the next lower surge drum 25 through a connection 32 and maintains a liquid level in the lower portion of the drum. Again excess liquid re-enters the return pipe 31 through connection 33 and passes downward to the next lower surge drum 25. Excess liquid ammonia from the lower-most surge drum 25 enters the return pipe 31 through a connection 33 and is returned to the upper portion of the master surge drum 12. Thus each surge drum 25 is maintained with an ample supply of liquid ammonia in its lower portion. At each level of the building, the low head ammonia pump 26 withdraws liquid ammonia from the bottom of the adjacent surge drum 25 and passes it through the distribution valve 27 into the cooling coil 28. A portion of the ammonia in coil 28 is expanded to a gaseous state in cooling the space 10, and mixed gas and liquid from the coil 28 is returned to the top of the surge drum 25 through connection 35. Gaseous ammonia flows from the upper portion of the surge drum 25 along with excess liquid ammonia through connection 33 into the return pipe 31 which, therefore, conducts mixed gaseous and liquid refrigerant downward and eventually into the upper portion of the master surge drum 12. Gaseous ammonia is continually drawn off the top of the master surge drum through conduit 13 to the compressor 14 where it is compressed and delivered by conduit 15 to the condenser 16. The compressed gas is liquefied in the condenser 16 and then collected in the receiver 17 for automatic return as liquid ammonia to the master surge drum 12 for recirculation.

Where it is estimated that each of the five spaces 10 to be refrigerated may require about one gallon of liquid ammonia per minute, the high head liquid ammonia pump 22 should be of sufficient capacity to circulate about twenty-five gallons per minute of liquid ammonia upward through supply pipe 30 into the top surge drum 25. Such a capacity provides that there will always be ample liquid ammonia in the lower portion of each of the five surge drums 25.

The surge drum 25 and circulating pump 26 on each level of the multi-story building may be conveniently placed in a corner room 40, as shown in Figure 2. The outlet from each pump 26 may be connected to a header 41, and each of several cooling coils 28 on that level may be connected

to the header 41 by distribution valves 27. A similar header, not shown, may be used to collect the gaseous and liquid return from each coil 28 for passage through conduit 35 back into the surge drum 25. The location of the apparatus at each level in a separate room 40 provides easy access to the equipment for adjustment and repairs when necessary. The space 40 may be provided with windows 42 to allow cross ventilation of the apparatus in room 40 when required.

Whenever the apparatus on a given level requires repair or when a space 10 is to be temporarily without refrigeration, the valved connections 32 and 33 at that level may be closed after opening the adjacent valve 34 to permit the refrigerant flow in return pipe 31 to by-pass that particular level. At each level, an emergency connection 43 may extend from the supply pipe 30 to the header 41 or the distribution valve 27 to provide for supplying liquid ammonia direct from the supply line 30 to the cooling coil 28 in the event that pump 26 is out of operation for repair. However, valves 44 in the conduits 43 are normally maintained closed. There may also be provided at each level, a safety connection 45 extending from the coils 28 to a conduit 46 which enters the return line 31 at a low level. Each safety connection is normally closed, preferably by a conventional bursting disc 47 which will rupture if the refrigerant pressure in the cooling coil 28 ever should exceed the pressure in the return line 31 by about one hundred and fifty pounds per square inch.

There also may be provided a small diameter valved conduit 48 extending from the compressed gas conduit 15 upwards to the outlet of each cooling coil 28 for conveying hot gases for use in defrosting the coils 28 when required. The valves 49 should be kept closed except during a defrosting operation. The master surge drum 12 may be provided with a drain valve 50 and a pressure relief valve 51 as is well known in the art. A valved connection 52 may also be provided between the bottom of each surge drum 25 and the return line 31 for draining surge drum 25 of liquid ammonia or accumulated oil.

It will be apparent from the above description of the system illustrated diagrammatically in the drawings, that the system provides for individual space temperature control by individual thermostats 29 for controlling the low head liquid ammonia pumps 26. The volume of liquid ammonia in circulation under high head is only a small fraction of the total liquid ammonia in circulation, and thus pump wear, pump cost, and power requirements are minimized. The system provides for an emergency feed of liquid ammonia to the cooling coils 28 through conduits 43. Should a pump 26 be taken out of operation for any reason, the emergency line 43 can be used until the pump is repaired. Individual space temperatures are controlled with a very minimum of controls and no liquid level controls are required on any level except the float switch 19 on receiver 17. With the system herein described, the volume of ammonia charge is considerably less than when individual refrigeration systems are provided on each level. The use of the double pumping recirculating arrangement makes proper adjustment of the distribution valves 27 much easier than where a single pump central system is installed. With the system shown, no high pressure conduits are required to extend upwards through the building. The only high pressure liquid ammonia conduit is the line 18 extending from the

receiver 17 to the master surge drum 12 at the lower level. Another advantage of the system shown is the fact that the surge drum, low head pump and distribution headers at each level may be placed in a protected space 40 separate from the refrigerated space 10, thereby providing for easy ventilation and access.

This invention contemplates the use of various other form of pumps, surge drums, control valves, etc., as it will be readily apparent to the skilled refrigeration mechanic that such variations are possible within the scope of the following claims.

I claim:

1. A refrigerating system for multi-story buildings comprising in combination; refrigerant liquefying apparatus on a lower floor including a compressor, a condenser, a receiver, and a master surge drum for containing both gaseous and liquid refrigerant; space cooling apparatus on each of several upper floors including a surge drum, a refrigerant evaporator, and a pump for pumping refrigerant from said surge drum to said evaporator; a pump on said lower floor for pumping liquid refrigerant from said master surge drum into said surge drum on the uppermost floor to be cooled, conduits connecting each of said surge drums to the surge drum on the next lower floor, and a conduit connecting the lowermost surge drum to said master surge drum.

2. A refrigeration system for multi-story buildings comprising in combination; refrigerant liquefying apparatus on a lower floor including a compressor, a condenser, a receiver, and a master surge drum for containing both gaseous and liquid refrigerant; space cooling apparatus on each of several upper floors including a surge drum, an evaporator coil, a pump for pumping refrigerant from said surge drum to said coil, and thermostatic means in said space to be cooled controlling said pump; a high head pump on said lower floor for circulating liquid refrigerant from said master surge drum into said surge drum on the uppermost floor to be cooled, conduits connecting each of said upper floor surge drums to the surge drum on the next lower floor, and a conduit connecting the lowermost surge drum to said master surge drum.

3. A refrigeration system for multi-story buildings comprising in combination; refrigerant liquefying apparatus on a lower floor including a compressor, a condenser, a receiver, a master surge drum for containing both gaseous and liquid refrigerant, and a valved conduit for controlling the flow of liquid refrigerant from said receiver to said master surge drum; space cooling apparatus on each of several upper floors of said building including a surge drum, an evaporator coil and a pump for pumping liquid refrigerant from said surge drum to said coil; a pump on said lower floor for pumping liquid refrigerant from said master surge drum into the surge drum on the uppermost floor to be cooled, and conduits connecting each of said upper floor surge drums to the surge drum on the next lower floor and connecting the lowermost surge drum to said master surge drum.

4. A refrigeration system for multi-story buildings comprising in combination; refrigerant liquefying apparatus and a master surge drum on a lower floor; space cooling apparatus on each of several upper floors including a surge drum, an evaporator coil, a pump for pumping liquid refrigerant from said surge drum to said coil, and a return conduit from said coil to said surge drum; a continuous pump on said lower floor for

circulating liquid refrigerant from said master surge drum to the uppermost surge drum, a return conduit connecting said surge drums in series and connecting the lowermost surge drum to said master surge drum.

5. A refrigeration system for multi-story buildings comprising in combination; refrigerant liquefying apparatus and a master surge drum on a lower floor; space cooling apparatus on each of several upper floors including a surge drum, an evaporator coil, a pump for pumping liquid refrigerant from said surge drum to said coil, and a return conduit from said coil to said surge drum; a pump on said lower floor for circulating liquid refrigerant from said master surge drum to the surge drum on the uppermost floor to be cooled, a return conduit connecting said surge drums in series and connecting the lowermost surge drum to said master surge drum, and valved by-pass connections in said return conduit for passing circulating refrigerant by any of said upper floor surge drums.

6. A refrigeration system for multi-story buildings comprising in combination; refrigerant liquefying apparatus and a master surge drum on a lower floor; said liquefying apparatus being connected to said master surge drum for liquefying gaseous refrigerant and returning liquid refrigerant to said drum; space cooling apparatus on each of several upper floors including a surge drum, an evaporator coil, and a pump for pumping liquid refrigerant from said surge drum to said coil; a high head pump on said lower floor connected to said master surge drum, a supply conduit extending from said pump to the top of the uppermost surge drum, a return conduit connecting said surge drums in series and connecting the lowermost surge drum to said master surge drum, and valved conduits extending from said supply conduit direct to each of said evaporator coils for by-passing said surge drum and pump on any floor.

7. A refrigeration system for multi-story buildings comprising in combination; refrigerant liquefying apparatus and a master surge drum on a lower floor; said liquefying apparatus being connected to said master surge drum for liquefying gaseous refrigerant and returning liquid refrigerant to said drum; space cooling apparatus on each of several upper floors including a surge drum, a pump, and an evaporator coil; a pump on said lower floor connected to said master surge drum, a supply conduit extending from said pump on said lower floor to the uppermost surge drum, a return conduit connecting said surge drums in series and connecting the lowermost surge drum to said master surge drum, a separate return conduit extending from the uppermost floor to be cooled into said first-mentioned return conduit at a point above said master surge drum, and pressure relief connection between the outlets of said evaporator coils and said separate return conduit.

8. A refrigeration system for multi-story buildings comprising in combination; refrigerant liquefying apparatus and a master surge drum on a lower floor; said liquefying apparatus being connected to said master surge drum for liquefying gaseous refrigerant and returning liquid refrigerant to said drum; apparatus on each of several upper floors confined in a closed space on said floor and including a surge drum and a pump, an evaporator coil within a space to be cooled on said floor connected to said pump and said surge drum; a high head pump on said lower floor con-

connected to said master surge drum, a supply conduit extending from said high head pump to the uppermost surge drum, a return conduit connecting said surge drums in series and connecting the lowermost surge drum to said master surge drum.

9. A refrigeration system for multi-story buildings comprising in combination, refrigerant liquefying apparatus on a lower floor including a compressor, a condenser, a receiver, and a master surge drum for containing both gaseous and liquid refrigerant; space cooling apparatus on each of several upper floors including a surge drum, a refrigerant evaporator coil, and a pump for pumping liquid refrigerant from said surge drum to said evaporator coil; a pump on said lower floor connected to said master surge drum for pumping liquid refrigerant to the uppermost surge drum, conduits connecting said upper floor surge drums in series for returning liquid and gaseous refrigerant to said master surge drum, and a hot gas line extending from said refrigerant compressor to each of said evaporator coils for use in defrosting said coils.

10. A refrigeration system for multi-story buildings comprising in combination; ammonia liquefying apparatus on a lower floor including a compressor, a condenser, a receiver, and a master surge drum, said compressor being connected to the top of said master surge drum to draw gaseous ammonia therefrom and said receiver being connected to said master surge drum to return liquid

ammonia thereto; space cooling apparatus on each of several upper floors of said building including a surge drum, an evaporator coil, and a pump for pumping liquid ammonia from the lower portion of said surge drum into said evaporator coil, the outlet of said coil being connected to the upper portion of said surge drum; a high head pump on said lower floor connected to said master surge drum for circulating liquid ammonia from said master surge drum to the upper portion of the uppermost surge drum, a conduit connecting the central portion of said uppermost surge drum to the upper portion of the surge drum on the next lower floor, another conduit connecting the central portion of said last-mentioned surge drum with the top portion of a still lower surge drum, the lowermost surge drum being connected to the upper portion of said master surge drum for returning gaseous ammonia and excess liquid ammonia thereto for liquefaction and recirculation.
